UNITED STATES PATENT OFFICE.

FRANCIS H. HAMBLETON, OF BALTIMORE, MARYLAND.

STOP-VALVE.

SPECIFICATION forming part of Letters Patent No. 290,044, dated December 11, 1883.

Application filed August 21, 1883. (No model.)

To all whom it may concern:

Be it known that I, FRANCIS H. HAMBLETON, of the city of Baltimore, and State of Maryland, have invented certain Improvements in Stop-Valves, of which the following is a specification.

This invention relates to certain improvements in a valve especially designed for controlling the passage of atmospheric air to a vessel containing an inflammable gas; but it may be used for various other purposes.

In the drawings forming a part hereof, Figures I and II are views, as seen from different points, of portions of a gas-making apparatus to which my improved valve is applied. Figs. III and IV are enlarged views of the stop-valve.

Similar letters of reference indicate similar parts in all the views.

20 A is the shell of the valve, having the nozzles B, and C C are disks accurately faced to form valves or gates. The face of the valves and the valve-seats may be provided with brass rings *a* and *b*, to admit of repairs, as shown in the drawings; but these rings are not necessary to the operation of the valve.

25 D is a cross-head, from which the disks C are suspended by means of rods *c*. These rods *c* pass through slots *d* in the cross-head D, which admits of the disks being adjusted to the valve-seats, and the said rods are provided with collars and nuts, whereby, after the adjustment of the disks, the said rods may be fastened. E is the valve-stem, which passes 30 loosely through the upper end of the casing A, and it is threaded where it is inclosed by the cross-head D.

35 F is a wedge on the lower end of the valve-stem E, which in the turning of the valve-stem is either forced between or drawn from contact with the rounded projections G on the inner sides of the disks C.

40 From the foregoing description it will be understood that the disks and cross-head and 45 their attachments may be elevated or depressed by means of the valve-stem without the same being turned, and that the disks can be slightly forced outward or distended, when in place, by turning the said stem. In adjusting the disks it is designed to make them fit closely between the valve-seats, but without their exerting any great pressure thereon, and

this pressure of the disks on the valve-seats is of a yielding character, in view of the elasticity of the rods *c*. In forcing the wedge F 55 between the disks it is intended to only change this yielding valve, which consists of suspended disks, into a rigid device. To prevent the distention of the disks when the same are fully or partially elevated, I provide the valve-stem E with a grooved stop, H, having triangular deflecting-pieces *e*, and the shell A is fitted with ribs *f*, with which the stop H 60 engages as soon as the disks are slightly raised. It will be seen that the stop H has 65 four slots, *g*, and the same number of deflecting-pieces *e*. Consequently, in the elevation of the disks, the stem E cannot be turned more than a quarter of a revolution, which is not sufficient, after the wedge F has been withdrawn from contact with the curved surfaces 70 G, to distend the disks to such an extent as to cause distortion.

I is a safety-valve located in the bottom of the casing A, and held yieldingly to its seat 75 by means of a spiral spring, *h*, and a cross-bar, *i*. The lower end of the valve-stem is extended downward toward the safety-valve, so that it will depress and open the said valve therefor to its full extent when the disks are 80 closed, and when the disks are raised the valve I is closed by its spring. Consequently air or gas can pass through the valve without escape. When the disks are closed and the safety-valve I open, any leakage of air or gas has 85 free access to the outer air.

To fully understand the principal use to which I design to apply this valve, reference should be had to Figs. I and II, in which K and L are respectively the generator and the 90 main air-blast pipe of a water-gas apparatus. In this apparatus the air-blast is intermittently forced to the generator K through the pipes M and N, in the latter one of which the improved valve is located. Now, when the 95 air-blast is stopped, the gas-pressure in the generator K exceeds that of the air in the blast-pipe. It follows, therefore, that if the valve is not absolutely tight gas escapes past the disks C and, if there is no means of escape, mixes with the air in the blast-pipe and forms an explosive mixture. With my valve 100 this mixing of gases cannot occur, as the gas, in seeking the means of escape offering the

least resistance, passes the safety-valve I to the outer air. The moving parts of the valve are counterbalanced by a weight, which is attached to a swivel, O, (shown in Fig. I,) on the end of the valve-stem, by means of a cord passing over a sheave. The turning of the valve-stem is accomplished by hand through the medium of a wheel on lever P.

I claim as my invention—

1. In a stop-valve, the combination of a non-rotative cross-head adapted to have a vertical sliding movement in the valve-shell, a pair of disks or gates suspended from the said cross-head by means of rods, a sliding valve-stem threaded where it passes through the said cross-head, and a wedge attached to the lower end of the valve-stem, which in the turning of the said stem is either forced be-

tween or removed from contact with the said disks, substantially as and for the purpose specified.

2. In a stop-valve, the disks thereof, suspended from a cross-head by means of rods which pass through slots in the said cross-head, whereby the said disks may be adjusted to their seats, substantially as specified.

3. In a stop-valve, the shell thereof, provided with an inwardly-projecting rib, and the stem with a slotted stop, which in the opening of the valve engages with the said rib and prevents the turning of the stem, substantially as and for the purpose specified.

FRANCIS H. HAMBLETON.
